CONVEX SCREEN VIEWBOX

James A. Tamborello, North Hollywood, Calif., assignor
of fifty percent to Miyamoto Osamu, Arcadia, Calif.

Filed Mar. 20, 1969, Ser. No. 16,339

Term of patent 14 years

Int. Cl. D16—99

U.S. Cl. D61—1

FIG. 1 is a perspective view of the front face of the convex screen viewbox in accordance with the invention; and

FIG. 2 is a perspective view of the rear portion of the convex screen viewbox.

I claim:

The ornamental design for a convex screen viewbox, substantially as shown and described.
